UNITED STATES PATENT OFFICE.

CHARLES H. RAUEN, OF SEATTLE, WASHINGTON.

DESIGN FOR A SUGAR-BOWL.

48,761.

Specification for Design.

Patented Mar. 21, 1916.

Application filed January 28, 1916. Serial No. 74,515. Term of patent 7 years.

To all whom it may concern:

Be it known that I, CHARLES H. RAUEN, a citizen of the United States, and resident of the city of Seattle, county of King, State of Washington, have invented a new, original, and ornamental Design for Sugar-Bowls, of which the following is a specification, reference being had to the accompanying drawing, forming a part thereof.

Figure 1 is a side view of a sugar bowl of my new design. Fig. 2 is a top view of the same.

What I claim is:

The ornamental design for a sugar bowl substantially as herein shown.

Signed at Seattle, Washington, this 19th day of January, 1916.

CHARLES H. RAUEN.
